UNITED STATES PATENT OFFICE

2,509,373

EYE MOVING MECHANISM FOR DOLLS

Florence M. Stevens, Aurora, Ill.

Application November 4, 1947, Serial No. 784,003

1 Claim. (Cl. 46—169)

1

This invention relates to dolls and more particularly to eye animating means for dolls, and the like.

A main object of the invention is to provide a novel and improved eye moving mechanism for dolls made of rubber or other deformable resilient material, said mechanism being operable by pressure applied to the body of the doll and being simple in construction, reliable in operation and light in weight.

A further object of the invention is to provide an improved eye animation mechanism for rubber dolls and the like, which is inexpensive to manufacture, durable in construction and easy to operate.

Further objects and advantages of the invention will become apparent from the following description and claim, and from the accompanying drawings, wherein:

Figure 1 is a vertical cross-sectional view taken through the head and upper body portion of a rubber doll provided with eye animation means constructed in accordance with the present invention.

Figure 2 is a vertical cross-sectional view of the doll structure of Figure 1, taken transversely with respect to Figure 1.

Figure 3 is a side elevational detail view of the main actuating unit of the eye animation mechanism employed in the doll structure of Figures 1 and 2.

Figure 4 is an enlarged horizontal cross-sectional view taken on line 4—4 of Figure 2.

Figure 5 is an enlarged cross-sectional detail view taken on line 5—5 of Figure 2.

Figure 6 is an enlarged detail elevational view showing the end structure of a rack bar employed for operating the eye animation mechanism of Figures 1 and 2.

Referring to the drawings, 11 designates a flexible-walled hollow doll of rubber or other suitable resilient material, the head of the doll being designated at 12 and the neck portion of the doll being designated at 13. The head of the doll is formed with eye openings, shown at 14, 14 and rotatably secured in said eye openings by annular seat-defining elements 15, 15 secured to the inner wall surface of the doll adjacent the respective eye openings are simulated eye balls 16, 16.

Designated at 17 is a generally cylindrical sleeve member, preferably made of sheet metal having interlocked vertical edge portions as shown at 18 to define the aforesaid cylindrical sleeve. The sleeve is reduced at 19 to define an annular groove 55

adapted to be interlocked inside the neck portion 13 of the doll, whereby said sleeve member will be supported in vertical position in the doll. The upper portion of sleeve member 17 is formed with a rear extension 20 which functions as a guard means for the eye animating link elements presently to be described.

Journalized in the lower portion of sleeve member 17 is a horizontal shaft 21, said shaft having tapered ends which are rotatably received in respective openings 22, 22 formed in the sleeve member. At its intermediate portion, shaft 21 carries a gear 23 and a circular disc 24 preferably secured to said gear. Slidable transversely through opposed square openings 25, 25 formed in the sleeve member 17 is a squared rack bar 26, whose teeth are meshed with gear 23. The rear end of rack bar 26 is provided with a detachable tip 27 which is secured to the bar end after said end is inserted through the associated square opening 25 of the sleeve member 17 during the assembly of the doll. Said tip is required to provide the necessary length of the rack bar for operating the eye animation mechanism by pressure on the front or rear wall of the doll body, as will be presently described. In view of the limited space inside the doll body, the tip 27 must be removed when the mechanism is inserted in said body and is screwed onto the end of the rack bar after the insertion of the mechanism has been accomplished.

Pivots connected to disc member 24 is an upwardly extending link rod 28. The top end of link rod 28 is pivotally connected to a U-shaped 35 yoke member 29 at the cross-arm 30 of said yoke member. The ends of the side arms of yoke member 29 are respectively rigidly connected to the eye balls 16, 16 at 31, 31.

When the doll body is pressed either at the front or rear thereof, the body wall thereof engages either the forward end of rack bar 26 or the rear tip 27 and causes the rack bar to move longitudinally thereof in the square guide openings 25, 25 of sleeve member 17. This rotates gear 23, and disc member 24 is likewise caused to rotate. Link rod 28 is thereby moved downwardly and oscillated either counter-clockwise or clockwise with respect to yoke 29, as viewed in Figure 2, depending upon whether pressure is applied to the rear or the front of the doll body. The movement of rod 28 is transmitted to the eyeballs 16, 16 by the yoke member 29, causing said eyeballs to rotate. The movement of the eyeballs is very life-like and greatly enhances the interest of the child in the doll.

While a specific embodiment of a doll eye animation mechanism has been disclosed in the foregoing description, it will be understood that various modifications within the spirit of the invention may occur to those skilled in the art. Therefore, it is intended that no limitations be placed on the invention except as defined by the scope of the appended claim.

What is claimed is:

In a doll having flexible body walls, eyeballs rotatably mounted in the head of the doll and means for rotating said eyeballs responsive to the flexure of a body wall of the doll, said means comprising a vertical, cylindrical sleeve member open at the ends thereof and formed with an annular recess interlocked with the restricted walls of the doll defining the neck thereof, a rack bar slidably carried by the walls of said sleeve member transversely thereof and extending therefrom for

engagement with said body wall, a gear rotatable in said sleeve member meshing with said rack bar, a disc in said sleeve member rotatable with said gear, a link rod pivotally connected to said disc, and a U-shaped yoke member having its side arms rigidly connected to the eyeballs and pivotally connected at its cross arm to the end of the link rod.
